PATENTED NOV. 24, 1903.

C. W. TREMAIN.

GAS ENGINE.

APPLICATION FILED AUG. 30, 1901.

NO MODEL.

UNITED STATES PATENT OFFICE.

CHARLES W. TREMAIN, OF CHICAGO, ILLINOIS, ASSIGNOR OF ONE-HALF
TO FRANK E. TREMAIN, OF CHICAGO, ILLINOIS.

GAS-ENGINE.

SPECIFICATION forming part of Letters Patent No. 745,266, dated November 24, 1903.

Application filed August 30, 1901. Serial No. 73,889. (No model.)

To all whom it may concern:

Be it known that I, CHARLES W. TREMAIN, a citizen of the United States, residing at 886 Warren avenue, Chicago, in the county of Cook and State of Illinois, have invented certain new and useful Improvements in Gas-Engines, of which the following is a specification.

My invention relates to improvements in gas-engines of the two-cycle type.

The principal object of my invention is to provide such an engine so constructed that the expansion of gases therein may be utilized as the motive force until such gases have expanded to substantially atmospheric pressure. This I accomplish, generally speaking, by utilizing the initial expansion of the gases to drive the piston in one direction and the further expansion of the gases to assist the return stroke of the piston and so, also, to assist in the compression of the explosive mixture in the compression-cylinder.

So it is among the objects of my invention to produce a higher and purer compression of the explosive mixture and to obtain greater efficiency from the quick and complete expansion thereof, together with an accelerated movement of the piston at every stroke.

A further object of my invention is to produce an engine of this type which shall involve reduced friction, less vibration, have a mild exhaust without the aid of a muffle, and which may be operated in either direction without manipulating the valve-gear.

All engines of this type are operated primarily by admitting an explosive mixture to a cylinder containing a piston and then igniting such mixture, the resultant expansion of the explosion of the mixture forcing the piston lengthwise of the cylinder. As commonly constructed when the piston reaches the end of its stroke the still heated and still expanding gases are allowed to escape from the cylinder through the exhaust. Careful tests have demonstrated that with an engine so constructed the gases escape from the exhaust at a high pressure and at a high temperature. Consequently this construction not only results in a great waste of power, but, owing to the high pressure at which the gases

escape through the exhaust, such engines produce a very noisy exhaust, which renders them unsuitable for many purposes.

Broadly speaking, my invention consists in providing the expansion-cylinder with a piston provided with a stem, all so proportioned and arranged with relation to each other that the free space within the expansion-cylinder is reduced to an annular explosion-chamber, while that portion of the piston-head which forms a movable end wall for said explosion-chamber and which is subjected to pressure of the expanding gases within the explosion-chamber has but a part of the total area of the piston-head.

Adjacent to the extreme outer end of the explosion-chamber is an expansion-chamber, free communication between which and the explosion-chamber is opened as the piston reaches the end of its forward stroke. The surface of the piston-head, which is exposed to the pressure of gases within this expansion-chamber, is so proportioned with relation to the area of the opposite face of the piston-head, which is exposed to the expansion of gases within the explosion-chamber, that when the expanding gases escape from the explosion-chamber into the expansion-chamber their pressure against the outer face of the piston-head will tend to force the piston back into the explosion-chamber, and thus assist the piston on its back stroke. As the back stroke of the piston carries the piston-head into the explosion-cylinder the cubic area of the expansion-chamber increases until the gases have expanded to or below atmospheric pressure, whereupon upon the next forward stroke of the piston the cooled and expanded gases are forced from the exhaust without heat, pressure, or noise. It will thus be seen that I not only utilize the secondary expansion of the gases to accelerate the return stroke of the piston, but where the engine is constructed as shown in the drawings, so that the piston is provided with a secondary piston-head, which moves within a compression-cylinder, so that the return stroke of the piston is utilized to compress the explosive mixture, I succeed by means of this secondary expansion of the gases in pro-

ducing a greater compression of the explosive mixture than could otherwise be readily obtained, which in turn results in a greater efficiency when the mixture so compressed is 5 exploded in the explosion-cylinder.

These and such other objects as may hereinafter appear are attained by the devices illustrated in the accompanying drawings, in which my invention is shown as embodied in 10 an engine of the oscillating class although my improvement is not confined to use in connection with this class of motor.

In the accompanying drawings, Figure 1 is a horizontal section of an oscillating engine 15 embodying my improvements. Fig. 2 is a side view, partly in section and partly in elevation. Fig. 3 is a view, partly in section, on the line 3 3 of Fig. 2 looking in the direction indicated by the arrows; and Fig. 4 is a 20 similar view on the line 4 4 of Figs. 1 and 2 looking in the direction indicated by the arrows.

Like characters of reference indicate the 25 same parts in the several figures of the drawings.

The form of engine shown is provided with an explosion-cylinder A, arranged tandem with a compression-cylinder B. C is a piston provided with piston-heads *a* *b*, fitting within 30 the cylinders A B, respectively. That portion of the stem of the piston C which is arranged to move within the explosion-cylinder A is so proportioned with relation to the piston-head and the explosion-cylinder that the 35 open space within the explosion-cylinder is reduced to constitute the annular explosion-chamber A', while the portion of the inner face of the piston-head *a* which is exposed to the pressure of gases within the explosion-chamber A' is reduced to the annular surface 40 *a'*, which constitutes a movable end wall to the explosion-chamber A'.

Opening from the forward end of the explosion-chamber A' is an expansion-chamber 45 D, arranged to be in free communication with the explosion-chamber A' as the piston-head *a* reaches the forward end of its stroke. The dimensions of the expansion-chamber D and the area of the outer face of the piston-head 50 *a*, which is exposed within the expansion-chamber D are so proportioned with relation to the area of the inner face of the piston-head *a* which is exposed within the explosion-chamber A' that when the expanding gases escape 55 from the explosion-chamber A' into the expansion-chamber D the continued expansion thereof will force the piston-head *a* backward into the explosion-chamber A'.

The piston-head *a* is provided with the 60 chamber 1, from which a port 2 communicates with the expansion-chamber D, while ports 3 3 communicate with the explosion-chamber A'. Mounted within the chamber 1 is a valve E, so constructed and arranged that when in 65 its extreme open position the area of the exposed outer face of the valve will be much

greater than the area of that portion of the inner face of the valve which is exposed to pressure within the chamber 1. In practice I have found it effective to have the area of 70 the exposed outer face of the valve three times that of the exposed inner face of the valve; but I do not confine myself to any such arbitrary proportions.

The expansion-chamber D is preferably provided with a number of diagonally-arranged supports *d* for guiding the piston-head *a* during its travel within the expansion-chamber D; but other suitable and well-known means 75 may be substituted for this purpose without departing from the spirit of my invention.

The compression-chamber B is provided with an explosive mixture through a pipe F, which passing through a slot *f* in the frame of the machine communicates with a passage 85 G, which opening through the trunnion H extends through the casing of the engine to a suction-valve I, whence a passage J communicates with the interior of the compression-cylinder. Upon the forward stroke of the piston 90 the explosive mixture is drawn into the cylinder B, whereupon on the back stroke of the piston the suction-valve I is automatically closed and the explosive mixture is forced out of the compression-cylinder through a 95 passage-way K, a check-valve L, a passage M, and thence into an annular passage N, which surrounds a piston-valve O and communicates with the piston side of said valve through ports P. From the piston-valve O a port or 100 passage Q communicates with the explosion-chamber A'.

By means of the eccentric R, mounted upon the axle of the fly-wheel, the strap S, and levers T and U the piston-head O is opened 105 during the return stroke of the main piston and is closed as soon as the charge of explosive mixture has been forced into the explosion-chamber A'. Thereupon by a suitable device, such as the sparker U, the mixture 110 within the explosion-chamber is ignited and expanding drives the piston-head A forward until the forward movement of the piston-head opens free communication between the explosion-chamber A' and the expansion-chamber D, whereupon the still-expanding 115 gases fill the expansion-chamber D and acting against the greater area of the exposed outer face of the piston-head *a* force the piston back within the expansion-chamber A', 120 at the same time forcing the valve E open. As the piston moves on its back stroke the gases remaining in the expansion-chamber A' escape through the ports 3 3 and the port 1 into the expansion-chamber D. At the same 125 time as the back stroke of the piston increases the space within the expansion-chamber D the gases within said chamber continue to expand, with a resultant decrease of pressure, and when the piston-valve O opens and admits 130 the explosive mixture under pressure to the explosion-chamber A the superior pressure

thereof exerted against the inner face of the valve E closes the valve E, and the engine is ready for the explosion of the charge and the next forward stroke. Meanwhile by means 5 of the rod V, connected with the gear of the engine and provided with an arm v, abutting against a collar w on the stem of the exhaust-valve W, the exhaust-valve is opened, and the next forward stroke of the piston forces 10 the now cool and expanded gases out of the exhaust without noise, pressure, or heat. As soon, however, as the next charge of expanding gases is admitted to the expansion-chamber D the exhaust-valve W is automatically 15 closed by the pressure of the gases within the chamber D, and the movement of the parts continues as before with constantly-accelerated speed.

While I have shown and described certain 20 means for admitting the explosive mixture to the compression-cylinder and for thence transmitting it to the explosion-cylinder, my invention is not confined to the employment of the precise means shown, as many ways 25 are known in this art for charging the compression and expansion cylinders of the engine, and, indeed, the means shown by me may be differently arranged—as, for instance, by arranging the supply-pipe F axially of the 30 trunnion H in a manner similar to that in which the water-pipe X for supplying the water-jacket is arranged in the trunnion H'. So, also, the sparking device U may be suitably attached to the expansion-cylinder at 35 any desirable point.

It will be observed that an engine constructed as above shown will readily operate the fly-wheel or a power-wheel in either direction, it only being necessary in starting the 40 engine to give the initial turn to the fly-wheel in the direction desired until the first charge has been compressed within the compression-cylinder and exploded within the explosion-chamber, whereupon the engine will continue 45 to operate without further manipulation until stopped in any usual manner.

I claim—

1. In an explosive-engine, the combination with an explosion-chamber and an expansion-chamber of larger diameter communicating therewith, of a differential piston fitted to said explosion-chamber, having its smaller area exposed within said explosion-chamber and arranged to open communication between 55 said chambers as it travels into the expansion-chamber, substantially as described.

2. In an explosive-engine, the combination with an explosion-chamber and an expansion-chamber communicating therewith, of a differential piston arranged to travel within said explosion-chamber, to open communication between said chambers as it nears the forward end of its stroke, and to close said communication on its return stroke, an exhaust-valve arranged to be actuated by pressure within said expansion-chamber to close an exhaust-port leading therefrom, and mechan-

ical means, actuated by said piston, to open said valve, substantially as described.

3. In an explosive-engine, the combination 70 with an explosion-chamber and an expansion-chamber communicating therewith, of a differential piston mounted within said explosion-chamber, having its greater area exposed within said expansion-chamber and arranged 75 to open communication between said chambers as it nears the end of its forward stroke and to close said communication upon its return stroke, said piston being provided with a passage therethrough from the explosion-chamber to the expansion-chamber, and a 80 pressure-actuated valve located in said piston and arranged to be opened by pressure within said expansion-chamber and to be closed by superior pressure within the explosion-chamber, substantially as described.

4. An explosive-engine, comprising an explosion-chamber, a piston provided with a piston-head arranged to travel within said explosion-chamber, an expansion-chamber, 90 means for controlling communication between said chambers, whereby said communication is opened as the piston-head nears the outer extreme of its travel and is closed upon the return stroke of the piston, said piston being provided with a passage-way for the escape of gases from the explosion-chamber upon the return stroke of the piston, and pressure-actuated means for closing said passage 95 when a fresh charge of explosive mixture is admitted to the explosion-chamber, substantially as described.

5. In an explosive-engine, the combination with a compression-cylinder, of an explosion-cylinder, an expansion-chamber communicating with said explosion-cylinder and of larger 105 diameter than said explosion-cylinder, a piston-head arranged to fit and travel within said compression-cylinder, and a piston-head so arranged to fit and travel within said explosion-cylinder that, as it approaches the end 110 of its outward stroke, it will open communication between said explosion-cylinder and said expansion-chamber, substantially as described.

6. An explosive-engine, comprising an explosion-chamber, an expansion-chamber of larger diameter than said explosion-chamber and communicating with one end of said explosion-chamber, and a piston arranged to fit 120 and travel within said explosion-chamber and to open communication between said explosion-chamber and said expansion-chamber, when near the outer end of its stroke, substantially as described.

7. An explosive-engine, comprising an explosion-chamber, an expansion-chamber of greater diameter than said explosion-chamber and communicating with one end of said explosion-chamber, a piston arranged to fit 130 and travel within said explosion-chamber, so as to open communication with said expansion-chamber, when said piston approaches the outer end of its stroke, the head of said

piston being provided with a valve-chamber, a port leading from said valve-chamber to said expansion-chamber, a valve arranged to alternately close and unclose said port, and
5 a passage providing communication between said valve-chamber and said explosion-chamber, substantially as described.

In testimony whereof I affix my signature in the presence of two witnesses.
